UNITED STATES PATENT OFFICE.

CHARLES C. HOGEN, OF CLEVELAND, OHIO.

COUPLING.

1,096,241.

Specification of Letters Patent. Patented May 12, 1914.

Application filed February 21, 1913. Serial No. 749,819.

To all whom it may concern:

Be it known that I, CHARLES C. HOGEN, a citizen of the United States, residing at Cleveland, in the county of Cuyahoga and 5 State of Ohio, have invented certain new and useful Improvements in Couplers, of which the following is a specification.

The invention relates to couplers, and constitutes an improvement over the structure 10 of my prior Patent 1,035,793, issued August 13, 1912. The invention has for its primary objects; the provision of a coupler of improved construction permitting the use of the coupler without additional links or other 15 devices upon sharp and reverse curves; the provision of a coupler having improved means for securing its vertical adjustment; the provision of a coupler having a pin and rollers as in my prior patented structure 20 above referred to in which the opposing lips engaging the rollers are spaced apart a sufficient distance to permit a substantial vertical movement of the coupler link, and in which the rollers are maintained in full 25 engagement with the said lips; the provision of a coupler of the character specified having improved means for securing the assemblage of the pin and rollers in the coupler pocket; and the provision of a coupler of the 30 character specified wherein the lateral movement of the link and rollers may be limited and adjusted as desired. Certain embodiments of the invention are illustrated in the accompanying drawings, wherein—

35 Figure 1 is a plan view of the coupling apparatus, with the parts in one position of use; Fig. 2 is a front elevation of the coupler head upon the bumper beam, with the rollers and link removed; Fig. 3 is a section 40 on the line III—III of Fig. 1, but with the rollers and link shown in position in the head; Fig. 4 is a section on the line IV—IV of Fig. 1; Fig. 5 is an end view of the securing pin shown in Fig. 3; Fig. 6 is a side 45 elevation of the rollers and pin as employed in the preferred type of construction; Figs. 7, 8, and 9, are sections through modified forms of pin and roller constructions, and Fig. 10 is a plan view of a modified form of 50 coupler head construction.

In Fig. 1 two forms of coupler head are illustrated, both of which, however, embody the same general principles of construction, the head A being of the type employed upon 55 the bumper beam of switching locomotive, and the head B having a shank correspond-

ing to that of the ordinary coupler and being applicable to the ordinary type of car. The two heads as illustrated in Fig. 1 show the position of the parts when the two cars are 60 upon a curve which causes the heads to shift laterally with respect to each other.

As indicated in Fig. 3 the head A is provided with a pair of overhanging lips 1 and 2, between which is the slot 3 for the usual 65 coupling link 4. Mounted in the head is the pin 5 carrying the rollers 6 and 7, such rollers engaging respectively the overhanging lips 2 and 1. As indicated in Figs. 3 and 6 the lower roller 6 is provided with a 70 perforation 8 extending clear through the roller, while the upper roller 7 is provided with a perforation 9 which passes only part way through the roller, so that when the roller 7 is placed upon the pin 5 it cannot 75 drop below the position indicated in Fig. 3.

The feature of supporting the upper roller 7 so that it cannot drop down below the position indicated in Fig. 3 is advantageous, as this permits the slot 3 to be made 80 as wide as may be desired, and at the same time insures that the entire bearing face of the roll 7 will always engage the overhanging lip 1. This would not be the case if the roller 7 were so constructed that it could 85 slide down until it engaged the coupler link as in my prior patented construction. It will be seen that it is important to have a relative wide slot 3 in order to permit of the vertical adjustment of the link 4, as the 90 coupler head with which the head A may be used may lie at a height considerably above or below the position of the head A, thus necessitating the tilting of the link either 95 upward or downward.

In order to permit of the assemblage of the pin 5 and rollers 6 and 7, a perforation 10 is provided through the bottom wall of the pocket A (Fig. 1). The head B has a corresponding perforation in its bottom wall 100 (Fig. 4), and in this head as in the head A (Fig. 2) the perforation is closed by a cap 11 which serves to prevent the pin from coming out accidentally after the parts have been assembled. This cap 11 is inserted 105 from the interior of the head, and is held against accidental displacement by means of a cotter 12. The closure means 11 is the same for the two heads A and B, the only difference being as to location, as indicated 110 in Fig. 1, and the construction will be readily understood by reference to Fig. 4 in con-

nection with Fig. 1. In assembling the parts the two rollers 6 and 7 are placed over the perforations in the bottom wall of the head, and the pin inserted from beneath, 5 the link 4 at such time of course lying between the two rollers. The parts are then moved from their position over the perforation and the cap 11 is inserted to prevent the accidental displacement of the pin subsequently.

In Figs. 7, 8, and 9, alternative arrangements are shown for maintaining the upper roller in its extreme upper position. In the construction of Fig. 7 the pin 5' carries the 15 rollers 6' and 7', the upper end of the pin being reduced as indicated at 13, in order to provide a shoulder to prevent downward movement of the roller 7'. This arrangement is less advantageous than the arrangement shown in Fig. 6, as the rollers 6' and 7' are not interchangeable. In the construction of Fig. 8 the pin 5'' carries the rollers 6'' and 7'', the upper roller being held against downward movement by means of the sleeve 20 14. In the construction of Fig. 9 the pin 5''' carries the rollers 6''' and 7''', the rollers being cast upon the pin so that the roller 7''' cannot approach the roller 6'''.

When the construction of Fig. 9 is employed the parts 25 cannot of course be assembled as heretofore described, and it is necessary to provide an opening into the interior of the head large enough to insert the three parts in their assembled position. This is done as indicated 30 in Fig. 2, by providing the opening 15 through the rear wall of the head, so that these parts are necessarily assembled before the head is applied to the bumper beam. When this construction is used the coupler 40 link must either be applied to the pin 5'' before the rollers are cast thereon, or else the link must be distorted in order to permit the passage of one of the rollers and subsequently pressed back into its proper place.

The head A is preferably held in place 45 upon the bumper beam 16 by means of the clamping members 17 and 18 (Figs. 1 and 2), such clamping members being secured in position by means of the bolts 19. In 50 order to make the support of the head more positive the beam 16 is preferably provided with the strap 20 (Figs. 1, 2, and 3), which strap is provided with a series of perforations 21. The coupler head is provided with 55 lugs 22 and 23 upon its upper and lower sides, which lugs have transverse perforations adapted to align with one of the perforations 21, depending upon the height to which the head is adjusted. A locking pin 60 24 passes through the aligned perforations and is held in place by a cotter 25. A considerable range of adjustment is thus secured, and the making of the head symmetrical upon its upper and lower sides permits of the use of the head with either side

down. The locking pin 24 is flattened upon one side as indicated at 26 in Fig. 5, so that it will fit close against the wall of the head, the cotter 25 passing through the wall of the header, preventing any outward movement. The upper wall of the header A is also provided with a perforation 27 (Fig. 1) for the reception of a cap corresponding to the cap 11, when the head is inverted.

The upper and lower walls of the head A 75 are provided with a series of perforations 28. When desired, the lateral movement of the rollers in the head may be limited by placing pins through these holes, such pins extending through the aligned holes in the upper and lower walls of the head. The holes also serve to drain the pockets between the stiffening ribs 29. In Fig. 2 a pin 30 is shown as extending through two opposing holes 28, for limiting the movement of 80 the rollers to the right.

The head B as shown in section in Fig. 4 corresponds throughout to the head A, except as to length, and with the further difference that this head is provided with the usual coupler shank. Pin 5⁴ and rollers 6⁴ and 7⁴ correspond throughout to the parts 5, 6, and 7 of the structure of Fig. 3, with the exception that the rollers are somewhat smaller. The parts are assembled through 90 a perforation in the bottom wall of the head as heretofore described, such perforation being closed by means of the cap 11, after the parts have been assembled. The top and bottom walls of the head B are provided 100 with the perforations 31, corresponding in function to the perforations 28 in the head A.

Fig. 10 illustrates a modified type of construction wherein the head 32 and bumper beam 33 are made in one integral casting 105 secured directly to the engine frame members 34-34. The rollers and pin used with this construction are precisely the same as in the construction of Figs. 1, 2, and 3, and the walls are provided with the perforations 110 35 corresponding in function with that of the perforations 28 in the construction of Fig. 1. The pin 36 is shown in position in one set of the holes 35, for limiting the lateral movement of the rollers in the head. 115 The central portion of the head is provided with a pair of aligned perforations 37 in the upper and lower walls, to permit of the insertion of an ordinary coupling pin when it is desired to use an ordinary coupling bar 120 or coupling link in the usual manner. Similar perforations 38 and 39 are provided in the heads A and B.

Having thus described my invention and illustrated its use, what I claim as new and 125 desire to secure by Letters Patent, is the following:

1. In combination, a hollow transversely extending head slotted along its front side and provided with opposing overhanging 130

5 lips spaced apart to permit vertical play of the hereinafter mentioned coupling link, a vertical pin in the head, a bearing roller on the upper end of the pin with its bearing edge in engagement with the upper lip and held against downward movement on the pin, whereby the said roller is maintained against decreasing its bearing engagement with the upper of the said overhanging lips,

10 10 a roller mounted on the lower end of the pin with its bearing edge in engagement with the lower lip, and a coupling link on the pin intermediate the rollers, the said rollers being spaced apart so as to permit a

15 15 vertical movement of the link along the pin.

20 2. In combination, a hollow transversely extending head slotted along its front side and provided with opposing overhanging lips and having its lower wall perforated to permit the passage of a bearing pin, a bearing pin, a lower roller perforated to permit the passage of the pin, an upper roller adapted to receive the upper end of the pin, interengaging parts on the pin and upper roller for preventing the upper roller from moving downward from its position at the end of the pin, and a coupling link lying between the overhanging lips and embracing the pin between the rollers.

25 20 3. In combination, a hollow transversely extending head slotted along its front side and provided with opposing overhanging

lips and having its lower wall perforated to permit the passage of a bearing pin, a bearing pin, a lower roller perforated to permit the passage of the pin, an upper roller adapted to receive the upper end of the pin, interengaging parts on the pin and upper roller for preventing the upper roller from moving downward from its position at the end of the pin, a coupling link embracing the pin between the two rollers, and means for closing the perforation in the lower wall of the head after the pin rollers and links have been assembled. 35 40 45

4. In combination, a hollow transversely extending head slotted along its front side and provided with opposing overhanging lips, a vertical pin in the head, bearing rollers on the ends of the said pin and engaging the said overhanging lips, and a link on the said pin, the upper and lower walls of the head being perforated on either side of the center line of the head to permit the insertion of pins to limit the lateral movement of the rollers and link. 50 55

In testimony whereof I have hereunto signed my name in the presence of the two subscribed witnesses.

CHARLES C. HOGEN.
